UNITED STATES PATENT OFFICE.

FREDERICK V. JARDEN, OF PHILADELPHIA, PENNSYLVANIA.

RAIL-JOINT.

SPECIFICATION forming part of Letters Patent No. 603,191, dated April 26, 1898.

Application filed September 22, 1897. Serial No. 652,547. (No model.)

To all whom it may concern:

Be it known that I, FREDERICK V. JARDEN, a citizen of the United States, residing in Philadelphia, Pennsylvania, have invented 5 certain Improvements in Rail-Joints, of which the following is a specification.

The object of my invention is to provide more efficient means than usual for supporting the meeting ends of railway-rails and for 10 tightening the fish-plates, so that the joint may be perfectly rigid in what are known as "bridge-joints"—that is to say, joints formed between the ties.

My invention is fully shown in the accompanying drawings, in which—

Figure 1 is a side elevation of my improved form of rail-joint. Fig. 2 is a transverse section on the line 1 1, Fig. 1. Fig. 3 is a detached perspective view of a part of the rail-joint. Figs. 4 and 5 are sectional views showing modified forms of the fish-plates. Fig. 6 is a plan view of a modified form of wedge-plate. Fig. 7 is a sectional view on the line 2 2, Fig. 6. Figs. 8 and 9 are sectional views 25 showing further modifications of the wedge-plate, and Figs. 10 and 11 are details of the invention.

My invention consists of a fish-plate rail-joint of the bridge type in which the wedge-plate has wedge-shaped ends engaging the depending portions of the fish-plates, the wedge-plate being adapted to be placed directly under 30 the meeting ends of the rails between two adjoining ties.

In the drawings, A represents the ordinary rail in general use, and B B are the fish-plates, which engage the head and base of the rail, as shown, and have depending portions B' midway between their ends, these depending 40 portions passing down between the ties upon which the rails are placed. The wedge-plate C (shown in the perspective view, Fig. 3) is placed directly under the meeting ends of the rails, so as to afford a solid support for the same, and a series of projections c are formed 45 on each side of the wedge-plate, which projections are adapted to fit the openings b in the depending portions B' of the fish-plates. These projections are beveled on their under side in 50 the same direction, so that after the wedge-plate is fitted in place movement of the same in the direction of the arrow, Fig. 2, will cause it

to be wedged between the base of the rails and the bottoms of the apertures in the depending portions of the fish-plates. In order to provide for positive movement of the wedge-plate and to keep it in the adjusted position, I provide one of the projections c, preferably the central one, with a threaded end c', to which a nut c² is adapted, said nut bearing against 55 an ordinary spring nut-lock c³. It is not essential, however, that this bolt be formed integral with the wedge-plate, and in Figs. 6, 7, and 8 I have shown a wedge-plate in connection with which a separate bolt may be used, 60 the squared head of the bolt fitting a recess c⁴ in the wedge-plate. This recess may be formed in the plate, as in Fig. 7, or may extend entirely through the same, as in Fig. 8, or the bolt may be tapped into a threaded opening in the wedge-plate, as shown in Fig. 9.

In Figs. 4 and 5 I have shown modified forms of fish-plates and bolts for holding the same to the rails. In the joints shown in these views the fish-plates are provided with 75 stepped or offset seats for the heads of the bolts and nut-locking washers, the washers being shown in Figs. 10 and 11, which are correspondingly stepped or offset. There is thus practically no danger of the bolts slipping or turning, and the loosening of the joint is thereby prevented. In lieu of the offset faces on the fish-plates, bolt-heads, and nut-locks, a depression, as b², may be rolled in the fish-plate, as shown in Fig. 1, with which the 80 bolt-head or washer may engage.

Should the joint work loose from any cause, it is only necessary to tighten the nut c² on the threaded end c', when the wedge-plate will be drawn up under the meeting ends of the rails, 85 thereby forming a solid support for the ends of the same.

The fish-plates are made alike, so as to be interchangeable, and the wedge-plate may be used on either side and the nut located on the 90 inside or the outside of the track structure, as may be desired.

I claim as my invention—

1. A joint for the meeting ends of railway-rails comprising fish-plates interchangeable 100 with each other and having depending portions with apertures therein having their lower faces on the same horizontal plane, a wedge-plate having beveled projecting mem-

bers forming wedges adapted to enter the apertures in the depending portions of the fish-plates, and likewise having their acting faces in the same horizontal plane, and means for 5 moving said wedge-plate laterally.

2. A joint for the meeting ends of railway-rails comprising fish-plates interchangeable with each other and having portions extending below the base of the rails with apertures 10 therein having their lower faces in the same horizontal plane, a wedge-plate having beveled projecting members forming wedges adapted to said apertures and likewise having their acting faces in the same horizontal plane,

15 with a bolt or bolts formed integral with the wedge-plate and a nut or nuts adapted thereto, whereby the wedge-plate may be moved laterally.

3. The combination of the rails, fish-plates 20 thereof, a wedge-plate mounted under the rails, said wedge-plate having beveled projections at each side bearing on the fish-plates, and a bolt carried by the wedge-plate above the bearing-point, with a nut adapted thereto 25 for moving the wedge-plate laterally, substantially as described.

4. As a new article of manufacture, a wedge-plate for the meeting ends of railway-rails

consisting of a body having on each side one or more projecting members beveled on the 30 under side, forming wedges, and having their acting faces in the same horizontal plane.

5. A joint for the meeting ends of railway-rails, comprising the fish-plates, and securing devices for holding said fish-plates to the 35 rails, said securing devices comprising bolts and nuts with suitable nut-locks, the seats for the bolt-heads and nut-locks having portions of their faces formed in different planes, the bolt-heads and nut-locks fitting the same, 40 whereby any rotative movement of the bolt is prevented.

6. As a new article of manufacture, a nut-lock comprising an annular ring of spring metal having a single plane surface on one 45 side of the same, and the other side composed of a number of surfaces offset from each other and in different planes.

In testimony whereof I have signed my name to this specification in the presence of two 50 subscribing witnesses.

FREDERICK V. JARDEN.
